J. D. SIBLEY.

Spirit Level.

No. 79,266.

Patented June 23, 1868.

United States Patent Office.

J. D. SIBLEY, OF MIDDLETON, CONNECTICUT.

Letters Patent No. 79,260, dated June 23, 1868.

IMPROVEMENT IN SPIRIT-LEVELS.

The Schedule referred to in these Letters Patent and making part of the same.

TO ALL WHOM IT MAY CONCERN:

Be it known that I, J. D. SIBLEY, of Middletown, county of Middlesex, and State of Connecticut, have invented an Improved Spirit-Level; and I hereby declare the following to be an exact description thereof, reference being had to the accompanying drawings, and to the letters of reference marked thereon, making a part of this specification, in which—

Figure 1 represents a perspective view of the instrument.

Figure 2, the pivot upon which it operates.

Figure 3 shows the shape and construction of the sights, and the manner in which they are attached to the level-frame.

Figure 4 represents a side view of the level.

The nature of the invention consists in the movable sights attached to the ends of any spirit-level frame, with a central pivot and circular disk for the level to revolve upon, the pivot being hollow, for the purpose of suspending a plummet-line and plumb attached.

A represents a circular disk or base, made of wood or metal. On the sides are marked the angles of degrees. In the centre of this horizontal disk is a hollow pivot, B, and in the centre of a carpenter's or mason's ordinary spirit-level I place a metallic socket, C, to operate on the pivot B.

On each end of the spirit-level frame I attach square metallic plates D D, with two grooves, E, in the top of the plates. Upon those plates D D, I affix two sights—one with the pin-hole eye-sight G, and the other, a sight, H, with two wire cross-lines, one a perpendicular and the other a horizontal line.

The bases of these sights G and H have flanges on their lower edges, so as to slide in the grooves E, in the plates D D, to always maintain their proper positions. They are then firmly fastened, by screws J J, to the spirit-level frame K.

On the upper side, and at the centre of the spirit-level frame K, is the horizontal spirit-level tube L, and at right angles with the spirit-level L is the spirit-level tube M, commonly called the perpendicular level, as attached to carpenters' or masons' ordinary levels.

The red lines across the disk A show how the spirit-level frame K can be revolved at any angle from the point of sight.

The advantage of my invention is, that more accurate levelling can be executed than heretofore, with a carpenter's ordinary level, for short distances, and at a very trifling expense. These sights, being movable, can be attached to any carpenter's ordinary spirit-level, and in combination with the socket C, pivot B, and circular disk or horizontal plate A, afford a very cheap and useful instrument for carpenters' and masons' uses, and so simple in construction that the youngest apprentice can accomplish the most accurate levelling.

What I claim as my invention, and desire to secure by Letters Patent, is—

The combination of the revolving sighted level with the disk A, when arranged and operating as herein described, and for the purposes set forth.

J. D. SIBLEY.
